His Attorney.

UNITED STATES PATENT OFFICE.

RALPH H. CHADWICK, OF FORT WAYNE, INDIANA, ASSIGNOR TO GENERAL ELECTRIC COMPANY, A CORPORATION OF NEW YORK.

ELECTRODE-HOLDER.

1,347,776.

Specification of Letters Patent. Patented July 27, 1920.

Application filed September 23, 1919. Serial No. 325,648.

To all whom it may concern:

Be it known that I, RALPH H. CHADWICK, a citizen of the United States, residing at Fort Wayne, in the county of Allen, State of Indiana, have invented certain new and useful Improvements in Electrode-Holders, of which the following is a specification.

My invention relates to electrode holders for holding carbon electrodes and the like. 10 More particularly my invention relates to manually manipulated electrode holders such as are used in soldering, welding and like operations depending on the heat generated by resistance of the electrode to the 15 passage of an electric current.

The object of my invention is to provide an improved holder of this type which is rigid and not easily liable to depreciation through use, and one in which supply or 20 renewal parts may be readily applied. A still further object of my invention is to provide an improved arrangement of parts whereby the power losses in the parts of the electrode holder itself, are materially reduced. 25

In accomplishing this end I have made use of a novel arrangement for securing together the several parts whereby a minimum of securing means are employed and 30 consequently little power is consumed in resistance joints, and the whole is quickly assembled and disassembled.

Also, those parts which are liable to be heated by eddy currents, such as are induced 35 where alternating currents are used in the electrode, are made of non-magnetic materials, thus materially reducing the inherent losses incidental to use of such electrodes.

For a more complete understanding of the 40 nature and objects of my invention reference should be had to the following detailed description when taken in connection with the accompanying drawing in which:

Figure 1 is a view, mainly in longitudinal section, of an electrode holder constructed 45 in accordance with my invention; while Fig. 2 is a view, principally diagrammatic, showing the application of my invention.

Referring now to the drawings, 10 represents a sleeve for the electrode holder 50 having a split portion 11 so as to readily receive a carbon or other suitable electrode, as indicated at C in Fig. 2. The split por-

tion 11 has a screw 12 working in a well known manner in the parallel ears 13, 55 formed on opposite portions of the split sleeve, in order that the electrode may be properly secured therein.

The sleeve 10 has formed integrally therewith, but projecting away from it, the shank 60 or elongated arm 14, which has an enlarged portion 15 adapted to be inserted in the cylindrical insulating member 16; the latter being suitably shaped for manual manipulation by the operator using my device. 65

The enlarged portion 15 has a central bore arranged to receive the bared end 17 of an insulated cable 18, which cable is adapted to be connected, as for instance as indicated in Fig. 2 to one terminal of a 70 transformer, for supplying current to the electrode C. The manual member, the electrode holder, and the cable are conveniently secured together by means of the screw 20. The screw 20 penetrates the wall of member 75 16 in register with a threaded opening in the wall of the enlarged portion 15, and bears upon the bared end 17 in order to force it into good electrical contact with the metal of the electrode holder. 80

A coiled spring 21 is inserted in the end of the manual member 16, surrounding the cable 18 as it emerges from the end of member 16 in order to take the edge strain, due to flexure of the cable, off that portion which is immediately exterior to the member 16, as is well understood. Such springs, have heretofore generally been made of steel, but where alternating currents are used to supply the electrical energy, such steel springs 90 become unduly heated by reason of the eddy currents induced therein; it is hence preferable to use springs of non-magnetic material such as phosphor bronze. 85

The electrode holder, which I have described, is particularly adapted for soldering, cutting, welding, and like operations utilizing the heat generated by the resistance of the electrode; the circuit supplying the electric energy, being led as indicated 95 from one terminal of a convenient source of E. M. F., as for instance the secondary S of the transformer T shown in Fig. 2, through cable 18 to the electrode C, thence through the "job" itself (not shown) to the 100 clip K which is attached during the opera- 105

tion to some convenient point on the "job" or job holding vise; and thence through the cable 23, attached to the clip, to the other terminal of the source of E. M. F. Such 5 transformer as has been indicated at T would be a step down transformer where the primary P was tapped onto a commercial lighting circuit.

The arm 14 is preferably of such length 10 that very little heat is conducted from the electrode C back to the member 16, but my improved means for uniting the elements of the electrode holder avoids all use of solder in making electrical connections. 15 Hence there are no parts to get loose or joints to depreciate or make bad electrical contact by reason of the heat conducted into the member 16 softening the solder which has heretofore generally been used. 20 Moreover the use of but one securing means, as at 20, makes the removal of an old holder 10 and the substitution of a new one very readily accomplished.

Having now described what is at present 25 the best means known to me for carrying out an embodiment of my invention, I would have it understood that such means are merely illustrative and that I do not mean to be limited thereby to the exact details 30 shown nor in the choice of recognized equivalents except as defined in my claims hereunto appended.

What I claim as new and desire to secure 35 by Letters Patent of the United States is:—
1. An electrode holder, comprising a sleeve member provided with a shank, an insulating member adapted to receive a portion of said shank, said portion being formed to receive an electric cable to be 40 electrically connected with said shank portion within said insulating member, and unitary means for uniting in operative re-

lation said insulating member, said shank and said cable.

2. An electrode holder, comprising a 45 sleeve member provided with a shank, an insulating member adapted to receive a portion of said shank, said portion being formed to receive an insulated electric cable having a bared end portion adapted to be 50 secured in electrical contact with said shank, and a securing means in the wall of said insulating member arranged both to hold said shank in place in said insulating member and to force said end portion of the cable 55 into electrical contact with said shank.

3. An electrode holder, comprising a sleeve member provided with a shank, an insulating member adapted to receive a portion of said shank, said portion being re- 60 cessed to receive an insulated electric cable having a bared end adapted to enter the recess formed in the shank portion within said insulating member, and a screw penetrating both the wall of said insulating 65 member and said shank and engaging said bared end of the cable when in said recess.

4. An electrode holder for use in connection with alternating currents, comprising an electrode holding sleeve provided with a 70 shank, an insulating member enveloping a portion of said shank and adapted for manual manipulation, said shank being adapted to receive a cable entering said member and to make electric contact therewith, a unitary means for securing said shank, member, and cable in operative relation, and non-magnetic means secured in said member for avoiding edge-strain on said cable at the point where it enters said member. 75 80

In witness whereof I have hereunto set my hand this 15th day of September, 1919.

RALPH H. CHADWICK.
